[57] CLAIM

The ornamental design for a table, substantially as shown and described.

DESCRIPTION

FIG. 1 is a perspective view of a table, showing my new design;

FIG. 2 is a side elevational view, the opposite side being a mirror image thereof;

FIG. 3 is a top plan view of the table of FIG. 1;

FIG. 4 is an end elevation of the table of FIG. 1, the opposite end elevation being the same;

FIG. 5 is a perspective view of a table, showing a second embodiment of my design wherein the top is square rather than rectangular; and,

FIG. 6 is an enlarged detail fragmentary elevation, front, rear or side at the corner of the top of the leg.

FIG. 1

FIG. 3

FIG. 2

FIG. 4

FIG. 5

FIG. 6
